UNITED STATES PATENT OFFICE.

JEAN ALEXANDRE REY AND JEAN MARC BARTHELEMY REY, OF PARIS,
FRANCE.

BOILER.

SPECIFICATION forming part of Letters Patent No. 698,140, dated April 22, 1902.

Application filed November 6, 1901. Serial No. 81,314. (No model.)

To all whom it may concern:

Be it known that we, JEAN ALEXANDRE REY and JEAN MARC BARTHELEMY REY, citizens of the Republic of France, residing at 5 Paris, France, have jointly invented certain new and useful Improvements in Steam-Generators, of which the following is a specification.

Our invention has relation to a steam-generator of the worm type, especially adapted to be heated by a hydrocarbon-burner and the tubes forming the worm or worms adapted to be in contact with the flame and gases of the burner, and in such connection it relates to the construction and arrangement of 15 such a generator or boiler.

The principal object of our invention is to provide a boiler or generator formed of a series of worms all joined together by separable 20 connections and arranged so that the heating of the worms shall take place progressively and regularly, the path of the hot gases from the source of heat being in a direction the reverse of the flow of the water and steam in 25 the worms.

The principal advantage of our present invention resides in the fact that the worms may be readily built up or taken away to increase or decrease the number of sections, 30 and hence to increase or decrease the capacity of the boiler, which in marine work is decidedly advantageous. Again, by arranging the worms in separable sections the pipes of the several worms may be of varying diameters and joined by detachable couplings 35 with adjacent worms, the pipes of which may be larger or smaller in diameter than the pipes of the worm to which it is connected. By this means the liquid may first travel through 40 a worm or worms having pipes of relatively small diameter and then through successive worms, the pipes of which are of relatively large diameter, so that the liquid as it expands into steam or vapor is conducted 45 through gradually larger pipes to prevent obstruction to the flow of steam or liquid.

The nature and scope of our invention will be more fully understood from the following description, taken in connection with the accompanying drawings, forming part hereof, in which—

Figure 1 is a vertical sectional view of a boiler embodying main features of our invention. Figs. 2 and 3 are views similar to Fig. 1, but illustrating modified forms of the 55 boiler. Fig. 4 is a vertical sectional view of a still further modified form of the boiler, in which provision for heating the air prior to its being fed to the burner or heating apparatus is shown; and Fig. 5 is a detail view 60 illustrating in vertical section the non-return valve on the liquid-inlet pipe.

Referring to Fig. 1 of the drawings, A represents the casing of the boiler, the cylindrical walls of the casing A having an inner 65 lining A' of refractory material. The bottom A² of the casing is closed save for a central opening A³, and the top A⁴ of the casing is also closed except for a central opening, upon which is fitted the stack or take-off pipe 70 A⁵, through which products of combustion are led off. The water-inlet pipe a is controlled by a non-return valve b and leads to the uppermost worm d in the series of worms d, e, f, g, and h, constituting the generator 75 or boiler. This worm d is arranged in a flat portion at the roof of the casing and in a tubular downwardly-projecting portion d', registering with the stack A⁵ in the roof of the casing A. The tubular portion d' is connected by a detachable coupling e' with the worm e, which, as shown, is also tubular like the worm portion d' and concentric therewith, so as to inclose the tubular portion d' of the worm d and extends upward toward 80 the roof A⁴ of the casing A. This worm e is connected at its upper end by a detachable coupling f' to the worm f, arranged in the form of a tube, adjacent to the insulation A' of the casing. This worm f communicates at 85 its base with the worm g by a U-shaped connection f². The worm g is in the shape of a hat, the brim of which rests upon the floor A² of the casing A and the crown g' of which extends upward from and registers with the opening A³ in said floor A². The top of the crown g' of the worm g is open and communicates, by a detachable coupling g², with an inverted-cup-shaped worm h, the tubular portion of which is concentric with and surrounds the crown g' of the worm g and the flat portion h' of which worm h extends above 90 95 100

and across the open top of the crown g' . The flat portion h' communicates by the pipe i with the point to which the steam is to be delivered. The flat portion h' supports a 5 plate h^2 , which is traversed by the pipe i , but otherwise seals the flat portion h' of the worm h to prevent the passage of hot gases directly through said portion h' . The pipe i traverses the interior of the worm d' and also penetrates the smoke-stack A^5 , as clearly shown. The worms constituting the generator are heated, preferably, by a hydrocarbon-burner, one form of which is illustrated in the drawings. The burner consists of a pipe k , leading 10 oil to the vaporizing-coil k' , which in turn discharges through the nozzle or pulverizer k^2 into the mixing-chamber m . Air is drawn into the chamber m through the openings l^3 by the passage of the vaporized oil into said chamber m from the nozzle k^2 . The mixing-chamber m is U-shaped and terminates in a burner m' , which projects upward into the coil k . The coil k' is situated below the floor A^2 of the casing A , but in alinement with the aperture or opening A^3 in said floor. The flame from the burner m' not only heats the vaporizing-coil k' , but passes upward through the opening A^3 and heats the interior of the crown g' of the worm g and the base h' of the 15 worm h . The gases are deflected downward by the base h' to heat the exterior of the crown g' , the interior of the worm h , and the flat or base portion of the worm g . The gases then pass upward between the exterior of the 20 worms h and e and the interior of the worm f and into the interior of the worm e , passing over the under face of the worm d and the exterior of the tubular portion d' . The gases are then deflected upward by the flat portion 25 h' of the worm h and the plate h^2 and flow through the tubular portion d' of the worm d into the smoke-stack A^5 . The passage of the gases is indicated by arrows in the various views.

45 It will be seen from the above description that in Fig. 1 the generator consists of a series of worms located above a central point and a second series of worms located below the central point, the two series being oppositely arranged—that is to say, the worm d , with its tubular extension d' , corresponds to the worm g , with its tubular extension g' , and the worms e and h correspond, but project in different directions from the common base, 50 which is the flat worm h' . The two series of worms thus described are inclosed in the tubular worm f , which is formed on the wall of the casing, and all the worms in the two series are so arranged that the hot gases are 55 obliged to lick the interior and exterior of the worms in each series and to lick the interior of the surrounding worm f before the gases enter the offtake or smoke-stack A^5 .

In the modification illustrated in Fig. 2 the 60 principle above set forth is also embodied; but in this form of the generator below the central flat worm p extends four concentric-

ally-arranged tubular worms g' , h , q , and f^{10} , respectively. Two of these tubular worms h and q have flat portions h' and q' , parallel 70 with the central flat worm p , and the worm g' has a flat base g , resting on the base A^2 of the casing A . Above the central flat worm extends similarly four concentrically-arranged tubular worms d' , e , r , and f^{11} , and parallel 75 with the roof A^4 of the casing is arranged the flat worm d , as in the form illustrated in Fig. 1. In the form illustrated in Fig. 2 the two outer tubular worms f^{10} and f^{11} are separated by a flue-space from the refractory wall A' of 80 the casing. The various worm-sections are connected together in this form by detachable couplings e' , r' , and f' and by detachable couplings g^2 , f^2 , q^2 , and p^2 , as clearly illustrated in the drawings. The path of the hot 85 gases in this form of apparatus is illustrated by arrows.

In Fig. 3 a further modified form of generator is illustrated, but the principle remains unchanged. In this form there are five concentrically-arranged tubular worms above and below a central flat worm p . Thus above the flat worm p are the tubular worms d' , e , r , s , and f , while below the flat worm are the tubular worms g' , h , q , t , and f . In this form 90 the worm f corresponds to the worm f of Fig. 1, inasmuch as it is continuous from top to bottom of the casing A and rests against the refractory wall A' of said casing.

In the forms illustrated in Figs. 2 and 3 two 95 plates h^2 and h^{10} are used to assist in preventing the passage of the gases directly up the smoke-stack A^5 .

In Fig. 4 an arrangement of worms is shown which is a duplicate of the arrangement shown 100 in Fig. 1. In this form, however, the refractory wall A' is dispensed with and the casing made double-walled. The space w between the walls of the casing A is utilized to receive 105 fresh air and to heat the same prior to its delivery to the mixing-chamber m of the burner. In Fig. 5 a preferred form of non-return valve 110 b on the water-inlet pipe a is illustrated. This valve b is an ordinary ball-check valve, which permits water to pass through it in one 115 direction, but prevents steam or vapor passing through it in an opposite direction.

As shown in all the forms illustrated in 120 Figs. 1 to 4, the upper worms, which contain the water partly warmed, but not yet vaporized, are formed of pipes the diameter of which is less than the diameter of the pipes forming the lower worms, which are closest to the burner m' . The lower worms contain 125 the vapor or steam, and their pipes are made larger in diameter to permit of the necessary expansion of the liquid after it becomes vapor or steam.

Having thus described the nature and object of our invention, what we claim as new, 130 and desire to secure by Letters Patent, is—

1. A steam generator or boiler, comprising a casing, a number of worms through which the liquid travels continuously, said worms

arranged in a double series of tubular worms located above and below a central flat worm, the series above the central flat worm being concentrically arranged with respect to each other and the casing and the lower series being concentrically arranged with respect to each other and the casing and the double series being arranged so as to form a continuous flue for the passage of the hot gases entering the base of the casing, said flue conducting the gases sinuously around surfaces of both series of concentric worms and of the central flat worm, in combination with a source of heat located below the lowermost worms.

2. A steam generator or boiler, comprising a casing, a flat worm located below the roof of the casing, a flat worm located above the base of the casing, a central flat worm located intermediately of the roof of the casing, a series of concentrically-arranged tubular worms located between the central flat worm and the roof of the casing, a similar series of tubular worms located below the central flat worm, all of said worms being detachably connected together to form a continuous passage for the water and steam, and all the worms arranged to form a continuous flue for the passage of hot gases entering the base of the casing, said flue conducting the gases to the interior and exterior surfaces of all the tubular worms and to the exposed surfaces of all the flat worms, in combination with a source of heat located directly below the lowermost tubular worm and an offtake located directly above the uppermost tubular worm.

3. A steam generator or boiler, comprising a casing, a flat worm located centrally within the casing, a series of tubular worms arranged concentrically with the wall of the casing and with each other located above the central flat worm, a second series of similarly-arranged tubular worms located below the central flat worm and having their pipes

larger in diameter than the pipes of the upper series, a water-inlet pipe discharging into the upper series of tubular worms, a steam-outlet pipe leading from the lower series of tubular worms and traversing the central flat worm, and the innermost tubular worm of the upper series, detachable couplings connecting all the worms together to form a continuous passage for the water and steam through the worms, in combination with a source of heat located below the lower series of tubular worms and an offtake located above the upper series of worms, the worms being arranged to form a continuous passage for the gases from the burner around all the worms and into the offtake.

4. A steam generator or boiler, comprising a casing, a double series of tubular and concentric worms arranged within the casing, a central flat worm above which one series of tubular worms is arranged and below which the other series of worms is located, the pipes of the worms above the central flat worm being of smaller diameter than the other worms, a source of heat located below the lower worms and a water-inlet pipe leading to the upper worms, said worms arranged so that the heat first traverses the space between the lower tubular worms and under the flat worm and then traverses the space between the upper tubular worms and over the flat worm, and a series of couplings connecting the various worms together to form a continuous passage for the water and steam through the worms.

In testimony whereof we have signed this specification in the presence of two subscribing witnesses.
